DRAPERY SLIDE FEEDING MACHINE

John Benedetto, 7441 Garden Grove Ave., Reseda, Calif., and Manfred Mandelbaum, 8641 Cadillac Ave., Los Angeles, Calif.

Filed Oct. 12, 1962, Ser. No. 230,212

10 Claims. (Cl. 29—241)

This invention relates to a device for feeding drapery slides or hangers in aligned oriented relation to facilitate stringing thereof on a curtain or drapery rod, it being an object of the invention to provide means not only facilitating stringing, but also aiding stringing of a required number of slides to speed up and, therefore, render slide-stringing operations economical.

Depending on the width of a curtain or drapery, the slide hangers required to properly hang the same vary between a few to twenty, thirty, or more for each of two curtains or draperies on a hanger rod. Stringing the exact number of such hangers on the rod, one at a time, particularly in cases where several drapery installations are being made, entails much loss of time that affects the cost of the work being done. Hence, the invention contemplates the provision of feed means that enables proper feeding of the required number of hangers on a rod in a time not much greater than needed to string two or three hangers one at a time.

Another object of the invention is to provide a drapery hanger feeding machine that feeds hangers from a hopper in which the hangers are in helter-skelter arrangement, and which aligns and orients them, leaving it for the operator only to slide them in easily defined and counted batches onto a curtain rod.

The above and other objects, features and advantages of the invention will become more clearly evident from the following description of a preferred form of the invention, the same having basis on the accompanying drawings in which like numerals designate similar parts in the several views, and in which:

FIG. 1 is a plan sectional view of a drapery slide feeding machine embodying features of the present invention.

FIG. 2 is a vertical sectional view as taken on the line 2—2 of FIG. 1.

FIG. 3 is a cross-sectional view, as taken on the line 3—3 of FIG. 2.

FIG. 4 is a cross-sectional view as taken on the line 4—4 of FIG. 1.

FIG. 5 is an enlarged and fragmentary plan view showing the portion of the machine that holds the hangers oriented and aligned preparatory to being fed or slid onto a hanger rod.

FIG. 6 is an end elevational view thereof.

FIG. 7 is a longitudinal sectional view as taken on the line 7—7 of FIG. 5.

The feeding machine that is illustrated comprises, generally, a base 10, a housing 11 extending upwardly from one end of said base, a hopper 12 for drapery slides disposed within said housing, a rotationally mounted and rotationally driven rotor 13 within said hopper to scramble the slides in the hopper, and to engage and feed the same successively toward the discharge end of the hopper, a slideway 14 extending from the hopper discharge to the opposite end of the base 10 receptive of slides fed thereto by the rotor 13 to present slides at the end of the slideway in aligned and oriented arrangement, and means 15 at said end of the slideway 14 to guide the location of a drapery or traverse rod 16 in end-to-end engagement with said end of the slideway, whereby a desired and variable number of slides may be moved from the slideway to the rod to obviate the need for singly counting out the slides being fed to the rod.

2

The base 10 comprises a generally rectangular tray with a bottom 20 and shallow encompassing walls 21.

The housing 11 has a preferably semi-cylindrical wall 22 extending as side walls 23 to the base 10, and front and back walls 24 and 25, respectively. The wall 24 is provided with an opening 26 eccentric to the housing wall 22 and with an inlet chute 27 through which drapery slides may be supplied to the machine for feed to the slideway 14.

10 The hopper 12 is shown as a conical container 28 within the housing 11 with larger circular end 29 affixed to the wall 25 and its smaller end 30 extending through the opening 26 and having an opening 31. Said inlet chute is open at 32 to the inside of the hopper 12, it being clear that slides may be supplied to the hopper through said opening 32.

The rotor 13 has a driven shaft 33 that is disposed longitudinally of the hopper and is eccentric therewith, as best seen in FIGS. 1, 3 and 4. In practice, said shaft may 20 be motor driven from the rearward end of the machine. Said rotor is shown as comprising a pair of oppositely arranged flat, strap-like members 34 that meet at a forwardly directed point 35 slightly inward of the opening 31 of the hopper and diverge rearwardly from said point 25 while in a common plane at about a 90° angle. At the rear said members 34 are curved out of said plane as at 36, in a direction to form scoops that impinge on and lift slides in the hopper when the rotor is rotated in the direction of the arrow 37 in FIG. 3.

30 The strap-like members 34 have outer edges 38 that hook onto slides S which have flanged studs 39 so said slides become hung up on the edge 38 of the member 34 that is moving in an upward arc through the supply of slides in the hopper. FIG. 2 shows a slide S so hung up, 35 and it will be clear that, as the member 34 approaches its topmost position (see FIG. 2), the slide is hanging freely on the edge 38 and will slide down on said edge and off point 35, due to the 45° angle of said edge, as shown. More than one slide S may become hooked on said edge 40 and the same will slide off the point 35 one after the other.

Not all of the slides S that become hung up on the edges 38, as first one member 34 and then the other dips into the supply of slides, scoops them up by means of 45 their curved ends 36, will become hooked; some will fall back into the hopper, others may become hooked but on the opposite side of the member 34 rather than on the side desired in position to deliver them properly to the chute 14. Lateral projections 41 are provided on each 50 member 34 extending from said opposite side thereof, the same being in the path of extensions 40 of slides improperly hung up and acting to dislodge the slides from their hanger edges 38 as they slide toward the point 35, so they 55 may fall back into the hopper 12. In this manner, assurance is had that only properly hung slides S will reach point 35 and proceed onto the slideway 14.

The eccentric relationship of the axis of the rotor 13 and the center of the hopper 12 provides a relatively large space in the hopper where the members 34 are 60 moving upwardly in a slide-scooping arcuate path. This space affords an opportunity for the hanger edges 38 to hook onto the flanged studs 39 of the slides. A too close position of said edges 38 to the wall of the hopper would cause the edges to move by without hooking onto slides, 65 while the members 34 bodily lift slides S which fall back into the hopper because there is no hooking engagement between the edges 38 and the flanged studs 39 of the slides.

Since many of the slides S that fall back into the hopper do so in close adjacency to the opening 31 and may clog the operation, the rotor is provided with paddle-like members 42 placed between the hanger mem-

bers 34 on both sides, and serving to stir around the slides S in the hopper in addition to whatever stirring action is afforded by the members 34. It will be noted that members 42 are nearer the central portion of the hopper than are the members 34 to provide efficient stirring around of the slides. Said members 42 are so formed as to push the slides rearwardly toward where the scoops 36 of the members 34 operate.

The slideway 14 slopes from a higher level where the same receives slides from the rotor 13 to the lower level at the forward end of the base 10. Said slideway comprises an elongated member 43 that has an end 44 immediately adjacent the point 35 of the rotor and is provided with an edge 45 that forms a sloping extension of whatever edge 38 of the rotor is in alignment therewith while the rotor is turning. Thus, a slide S sliding off the point 35 will slide onto said edge 45 and said slide will have a vertical disposition since, at the end 44, the member 43 is vertical.

Said member 43 is twisted through 90° from said upper end 44 to about its midpoint so the portion 46 has a generally horizontal disposition from said midpoint to the lower end thereof. It will be clear that slides that slide down along the member 43 will be quarter-turned from the vertical hanging condition to a horizontal flatwise disposition on the slide portion 46. Since the hanging edge 45 now is laterally directed, the slideway is provided with a strip 47 that is parallel to and spaced from said edge 45 to form a slide channel or path 48 for the flanged studs 39 of the slides. FIGS. 5 and 6 show the position of the slides with their extensions 40 resting lightly on the member 46 while the flanged studs 39 are confined to said channel.

The lower end of the slideway 14 is provided with a flat spring 49 that forms a lightly resilient release abutment to retain the slides from sliding off the end of the slideway under gravity. As seen in FIG. 5, the slides are retained by the end 49a of the spring 49 until one or more of them is manually pushed past said resilient abutment. The slides that follow will then fall by gravity until stopped by spring end 49a.

It will be noted that slide-counting marks or graduations 50 may be provided on the slideway, in this case on the strip 51 that carries the member 43 and strip 47. It is, therefore, a simple matter to slide the slides off the slideway in batches of the number desired without the need for separately counting them out.

The means 15 is shown as a channel 52 that extends forwardly from the base 10 with its longitudinal center aligned with the slideway channel or path. Said channel 52 locates the end of a curtain or traverse rod 16, as indicated in FIGS. 5 and 6, with its longitudinal slot 53 aligned with the mentioned slideway channel. As a consequence, slides S pushed off the slideway 13 have their flanged studs 39 moved into the slot 53, thereby providing the rod 16 with the slides thus removed from the slideway. A spring 54 in channel 52 serves to lightly clamp the rod 16 in its desired end-to-end abutting relation with the lower end of the slideway 14. This is clearly shown in FIG. 7.

Since the above-described feeding machine may be modified without departing from the spirit and scope of the invention, we do not wish that the claims be restricted, but rather desire that this disclosure be considered as exemplary of modifications that may fall within the scope of said claims.

We claim:

1. A feeding machine for hanger slides having stud hanger portions, comprising
  - (a) a hopper to loosely hold a supply of slides and having a front opening,
  - (b) a rotational rotor in said hopper provided with members having outwardly directed edges that are

4

sloped to a point directed toward and adjacent said opening and on the axis of rotation of the rotor, said edges engaging and hanging slides thereon to slide downwardly toward said rotor point, and

- (c) a slideway extending in a forwardly and downwardly sloping direction from said point and receptive of slides sliding off said rotor edges.

2. A feeding machine according to claim 1 in which the hopper is conical and in which the axis of the rotor is offset from the axial center of the hopper to provide a space between the hopper and the slide-hanging members of the rotor where the latter engage slides in the hopper to lift them.

3. A feeding machine according to claim 2 in which the slide-hanging members of the rotor are provided at their rearward ends with curved scoop portions on the same slope as the slope of the edges of the slide-hanging members.

4. A feeding machine according to claim 3 in which the rotor, in addition to the slide-hanging members, is provided with members to stir around the slides in the hopper during rotation of the rotor.

5. A feeding machine according to claim 1 in which the rotor is provided with projections that dislodge improperly hanging slides from the slide-hanging edges during sliding movement of said improperly hung slides toward the point of the rotor.

6. A feeding machine for hanger slides having stud hanger portions, comprising

- (a) a hopper to loosely hold a supply of slides and having a front opening,
- (b) a rotational rotor in said hopper provided with members having outwardly directed edges that are sloped to a point directed toward and adjacent said opening and on the axis of rotation of the rotor, said edges engaging and hanging slides thereon to slide downwardly toward said rotor point,
- (c) a slideway extending in a forwardly and downwardly sloping direction from said point and receptive of slides sliding off said rotor edges,
- (d) said slideway being provided with a member that has a 90° twist therein from a portion having a vertical disposition where the same receives slides from the rotor and a portion having a horizontal disposition, and
- (e) resilient means at the end of the latter portion to resist gravitational sliding of the slides along the slope of the slideway.

7. A feeding machine according to claim 6 in which the member with the twist therein has a hanger edge that is laterally directed where said member is horizontal, and a strip is disposed in spaced parallelism to said laterally directed edge to form a guide path of the slides.

8. A feeding machine according to claim 6 in which said resilient means comprises an elongated leaf spring with a slide-retaining spring end.

9. A feeding machine according to claim 7 in which is provided means to guide the location of a curtain rod in end-to-end relation with the lower end of the slideway with the conventional longitudinal slot therein in extension alignment with the guide path of the slideway.

10. A feeding machine according to claim 9 in which the slideway is provided with slide-counting marks to facilitate transfer of slides from the slideway to the curtain rod in predetermined numbers, as desired.
